SEATTLE, WASHINGTON, A CORPORATION OF WASHINGTON.

TIME-PRINTING MACHINE.

1,098,607.

Specification of Letters Patent.

Patented June 2, 1914.

Application filed December 30, 1912. Serial No. 739,327.

To all whom it may concern:

Be it known that we, EDWARD J. ARM-
BRUSTER and JAMES E. DEMPSEY, citizens of
the United States, residing at Seattle, in the
5 county of King and State of Washington,
have invented certain new and useful Im-
provements in Time-Printing Machines, of
which the following is a specification.

This invention relates to printing devices
10 and mechanism for operating the same at
predetermined times, and is particularly de-
signed for use with a cash-register or stock-
ticker, although the invention may advan-
tageously be employed in a number of other
15 applications.

Our invention has, primarily, for its ob-
ject to produce an efficient marking machine
which will register upon a paper, tape or
ribbon characters designating the time in
20 which portions of the paper are presented
into printing positions.

With this and other ends in view, the in-
vention consists in the novel construction
and combination of parts, as will be herein-
25 after described and claimed.

In the accompanying drawings, Figure 1
is a front elevation of an automatically op-
erated printing device embodying our in-
vention and with the containing case shown
30 in section and the printing mechanism in op-
erative position. Fig. 2 is a similar view
with the printing mechanism in inoperative
position.

In the drawings, the reference numeral 5
35 represents a casing inclosing the printing
mechanism and a time-motor or clock 6
whereby such mechanism is operated. A
movable frame comprised of arms 7 and 8
is fulcrumed by a pivotal pin 9 to a bracket-
40 support 10.

Journalized in the frame-arm 8 is a spindle
11 having mounted thereon a type-wheel 12
provided on its periphery with a series of
projections 12¹ carrying type-numerals des-
45 ignating successive periods of time, as "1",
"1:30", "2", "2:30", etc., to "12." To the
face of said wheel is a ratchet wheel 13
provided with teeth, corresponding in num-
50 ber to the number of projections 12¹ pro-
vided on the type-wheel.

The frame arm 7 is provided at opposite
sides of pin 9 with fingers 7¹ and 7² arranged

to coact with the teeth 14¹ of a cam-wheel 14
which is mounted upon a spindle 15 and is
movable in unison with a spur wheel 16 55
through the instrumentality of a pinion 17.
This pinion is mounted upon the arbor 18
which carries the minute hand of the clock
and, in consequence, is rotated once in each
hour, although it may be otherwise connect- 60
ed therewith as by an intermediate gear-
wheel, or by a train of wheels, to get any
other desired speed of rotation. Said pinion
is provided with two teeth 17¹ and 17²
disposed diametrically opposite each other, 65
hence the spur wheel is advanced thereby a
tooth, so to speak, every half-hour, resulting
in the cam-wheel 14 being similarly moved
to cause its teeth to successively encounter
the finger 7¹ of the frame and force the lever 70
arm 8 downwardly to swing the type-wheel
into printing position (see Fig. 1) and in
opposition to a spring 19 which serves to
restore the frame into its normal inopera-
tive position, in which it is shown in Fig. 2, 75
immediately after a tooth of the cam-wheel
has passed thereby. The office of the other
finger 7² is to limit the extent of the suc-
cessive movements of the cam-wheel.

20 represents a rod movable up and down 80
in guide-lugs 8¹ provided on the frame and
is formed at its lower end to serve as a pawl
with respect to the ratchet wheel 13; to
which end, the relatively weak spring 21 is
interposed between the upper of said guide 85
lugs and a head 20¹ provided on the rod and
tending to thrust the rod upwardly until ar-
rested by a fixed collar 20² on the rod engag-
ing the underside of the referred to lug.
When the frame arm 8 is swung upwardly, 90
said rod strikes against an adjustable stop
22 thereby interrupting the upward move-
ment of the rod during the terminal move-
ment of the arm. The spring 21 is thereby
caused to yield with a reverse movement be- 95
ing given to the rod, relatively to the frame
arm, whereupon the rod acts as a pawl to af-
ford an advance rotary movement to the
ratchet wheel and to the type-wheel which is
operable therewith, to progressively move 100
the type characters into printing positions.

23 represents a resilient blade which is
secured to the frame arm 8 and frictionally
presses against the face of the type wheel

to overcome any momentum thereto subsequent to the action of the pawl.

As illustrated, the casing is formed with a base element 5¹ and in the ends of the casing 5 are openings 5² and 5³ for the passage of a paper tape, indicated by 24, upon which time records are to be printed.

Immediately below the type wheel is an elastic-body or cushion 25 which serves as a 10 platen.

26 is an inking ribbon which is unwound from and wound upon spools 27 and 28, respectively positioned in spaced relations at opposite sides of the type wheel. The spools 15 are mounted upon spindles 27¹ and 28¹ journaled in suitable bearings provided, preferably, in the casing walls. The spool 28 is connected to its spindle to rotate therewith and provided on the latter is a ratchet wheel 20 29 which is given an intermittent rotary movement through the agency of pawl 30 carried by the frame-arm 7, as shown.

The operation of the invention is as follows: As the pinion 17 is rotated by the 25 clock arbor 18, the pinion teeth 17¹ and 17² are revolved to successively impart intermittent motion to the spur wheel 16 and likewise to the cam-wheel 14. When a cam-tooth is thus revolved, it actuates the frame 30 which carries the type wheel to swing the same down against the ink ribbon and the latter, in turn, against the article which is to be printed, to accordingly thereupon print the type characters as presented. 35 When this is accomplished, the spring 19 asserts its power to suddenly withdraw the type-wheel from the work and thus retain it until again affected by the following tooth of the cam-wheel. The type-wheel is progressively advanced as before explained, so as to 40 have the type characters record the progress of time.

What we claim, is—

1. In a time printing machine, a frame, a 45 rotatable type-wheel carried by said frame, a spring connected to said frame, clock-actuated devices acting in opposition to said spring for causing the frame to carry said type-wheel into printing position, and 50 means influenced by the successive movements of the frame to effect intermittent rotary movements to the type-wheel.

2. In a time printing machine, the combination with clock-work and a type-wheel, of 55 a spring for yieldingly maintaining the type-wheel in inoperative position, a cam wheel, a spur-gear operable in unison with said cam-wheel, and a pinion operated by said clock-work and adapted to actuate the 60 cam-wheel so as to coöperate with said spring to afford intermittent reciprocatory movements to the type-wheel.

3. In a time printing machine, a frame, a 65 rotary type-wheel carried by the frame, a cam for actuating said lever to move said

type-wheel into printing position, clock-work for operating the cam, a spring acting to retract the type-wheel from such printing position, and devices for rotatably moving the type-wheel when thus retracted. 70

4. In a time printing machine, the combination with clock-work and a type-wheel, of a spring for yieldingly maintaining the type-wheel in inoperative position, a cam-wheel, a spur-gear operable in unison with 75 said cam-wheel, a pinion operated by said clock-work and adapted to actuate the cam-wheel so as to coöperate with said spring to afford intermittent reciprocatory movements to the type-wheel, and ratchet and pawl devices made operative by said spring for imparting intermittent rotary motion to said type-wheel. 80

5. In a time printing machine, a vibratory frame, a type-wheel rotatably carried thereby, a spring tending to maintain said type-wheel in inoperative position, means actuated by clock-work for operating said frame to move the type-wheel into printing position and devices actuated by the power 90 of said spring for rotatably advancing the type-wheel. 95

6. In a time printing machine, the combination of a vibratile frame provided with a finger, a spindle carried by the frame, a type-wheel and a ratchet-wheel mounted on 100 said spindle, a spring connected to said frame and serving to yieldingly hold the same to retain the type-wheel in inoperative position, a cam-wheel provided with teeth 105 which are severally adapted to be engaged with said finger to swing the frame into printing position with respect to the type-wheel, gear-wheels for operating the cam, clock-work for actuating said gear-wheels, 110 a pawl engaging said ratchet-wheel, and adjustable means for limiting the action of said pawl whereby the amount of rotary motion given to the type-wheel is regulated, said pawl being actuated by means of a stop 115 coöperating with the intermittent swinging movement of said frame.

7. In a time printing machine, the combination of a vibratile frame provided with a finger, a spindle carried by the frame, a type-wheel and a ratchet-wheel mounted on 120 said spindle, a spring connected to said frame and serving to yieldingly hold the same to retain the type-wheel in inoperative position, a cam-wheel provided with teeth 125 which are severally adapted to be engaged with said finger to swing the frame into printing position with respect to the type-wheel, gear-wheels for operating the cam, clock-work for actuating said gear-wheels, and a pawl engaging with said ratchet wheel to impart rotary movement thereto in each movement of the same into inoperative position.

8. In a time printing machine, a vibra- 130

tory frame, a type-wheel carried by said frame, a toothed cam, clock-actuated means for imparting intermittent rotary movements to said cam whereby the teeth thereof will successively swing the frame into printing position with respect to the type-wheel, means acting in opposition to the cam-teeth for swinging the frame in a contrary direction, and means effected by the 10 swinging of the frame for imparting intermittent rotary movements to the type-wheel.

9. In a time-printing machine, the combination with a record-strip and a non-movable platen, of a series of type characters, 15 clock mechanism, and devices actuated by said clock mechanism for causing said type characters to successively strike against and imprint the same upon said record-strip in opposition to the platen.

10. In a time-printing machine, a wheel arranged for reciprocatory movements provided with peripherally disposed type characters, and clock-actuated means for progressively rotating said wheel and subsequently influencing the wheel to effect the 20

printing upon an article of the successive type characters of the wheel.

11. In a time-printing machine, a stationary platen, a rotary type-wheel, clock-actuated means for imparting intermittent rotary and reciprocatory movements to the wheel and cooperating with said platen for periodically impressing time-designating printed characters upon an article. 35

12. In a time-printing machine, a frame, a rotatable type-wheel carried by said frame, devices actuated by clock-work for causing said frame to first impinge the type-wheel against a platen and subsequently withdraw the type-wheel from the platen, and means influenced by the alternate movements of the frame to impart rotary movements to the type-wheels. 40

Signed at Seattle Wash., this 24th day of December, 1912. 45
